UNITED STATES PATENT OFFICE.

ARTHUR WHITE AND JACOB J. MOHR, OF SHEBOYGAN FALLS, WISCONSIN.

CONCRETE-MOLDING MACHINE.

Application filed May 1, 1925. Serial No. 27,191.

To all whom it may concern:

Be it known that we, ARTHUR WHITE and JACOB J. MOHR, citizens of the United States, and residents of Sheboygan Falls, in the county of Sheboygan and State of Wisconsin, have invented new and useful Improvements in Concrete-Molding Machines, of which the following is a description, reference being had to the accompanying drawings, which are a part of this specification.

This invention relates to improvements in concrete molding machines.

Concrete molding machines as now ordinarily used are adapted to manufacture one or two blocks at a time, and as comparatively considerable time is required before the concrete will set and harden to permit removal from the mold, the blocks cannot be manufactured very expeditiously, and therefore the cost is materially increased.

It is one of the objects of the present invention to overcome the before mentioned objectionable features and provide a concrete molding machine with which comparatively a large number of blocks may be made at the same time.

A further object of the invention is to provide a concrete molding machine in which the forms may be removed from the blocks without disturbing the blocks as soon as the concrete has set to permit more rapid hardening of the blocks.

A further object of the invention is to provide a concrete molding machine in which all of the block cores may be easily locked to a frame to permit raising all of the cores with the forms at the same time.

A further object of the invention is to provide a concrete molding machine in which the core lifting frame may be raised independently of the cores if desired to fill the forms or gain access thereto.

A further object of the invention is to provide a concrete molding machine having means for easily raising and holding the forms and the cores in elevated position until the concrete blocks are sufficiently hard to be removed.

A further object of the invention is to provide a concrete molding machine arranged so that the machine may be run into a heating means to more quickly harden the blocks to expedite their removal from the machine.

A further object of the invention is to

provide a concrete molding machine having molding sections which may be placed one above the other in spaced relation to form tiers of molding sections and which sections may be easily removed one at a time to permit easy removal of the completed blocks from the machine.

A further object of the invention is to provide a concrete molding machine in which several tiers of blocks may be molded in the machine at the same time.

A further object of the invention is to provide a concrete molding machine which is of simple construction, is strong and durable, and is well adapted for the purpose described.

With the above and other objects in view, the invention consists of the improved concrete molding machine and its parts and combinations as set forth in the claims, and all equivalents thereof.

In the accompanying drawings in which the same reference characters indicate the same parts in all of the views:

Fig. 1 is a side view of the improved concrete molding machine, parts broken away and other parts being shown in section;

Fig. 2 is an end view thereof, parts broken away and other parts being shown in section;

Fig. 3 is a top view of the form and core frame shown removed from the machine, parts broken away;

Fig. 4 is a detail view of the frame shown on a larger scale;

Fig. 5 is a sectional detail view of the side portion of the frame; and

Fig. 6 is a detail side view of a portion of the frame and the machine.

Referring to the drawings, the numeral 8 indicates a lower rectangular frame member which is preferably provided with transverse axles 9 upon which are journaled 100 wheels 10 to permit the machine to be easily moved into a curing room or other means to expedite the setting of the blocks. Said lower rectangular frame member or section comprises channeled side and end members 11 and 12 and a bottom member 13 all bolted together to form a rigid construction. The corner portions of the frame member have upright members or supports 14 removably resting thereon which form legs 110 of a second rectangular frame 15 positioned thereabove in spaced relation. Upright

members 14' extend removably upwardly from the corner portions of the second frame member and form legs of a third frame section or member 16 also mounted in spaced relation thereon. The rectangular frames and their legs form removable independent sections adapted to be placed one above the other during the molding operation, and in order to firmly hold the sections together 10 the lower end portions 14' of the legs 14 fit into the corner portions of the frame below and the shoulders 14'' of said legs rest upon said frame. Said frame members are all of the same size and shape and each 15 one is provided with a bottom portion 13' similar to the bottom portion 13 before mentioned. The frame members, legs and bottom portions thus far mentioned are connected together to form each section 20 into a rigid structure. Each frame section is provided with a block mold frame member 17 which is divided by partitions 18 and 19 to form the shaped block desired. In the present instance, the mold member is 25 adapted to form angular or T-shaped blocks which in use interfit each other. The partitions 18, including the side walls, extend longitudinally of the frame and their opposite end portions are bolted to the end 30 members 20 forming the opposite ends of the mold member while the transverse members 19 are interposed between the side and longitudinal members and are welded, riveted or fastened thereto in any manner desired. 35 The lower edge portions of the longitudinal partitions are arranged to fit into grooved portions 13'' of the bottom portions 13 to form a tight joint, and if desired the corner edges of said joints may be rounded to form 40 rounded edges on the blocks, as indicated in Fig. 2. Fig. 5 shows one form of connection in which the transverse members 19 are provided with tongues 19' which extend through perforations 18' formed in the 45 side and longitudinal members. The ends of the tongues may be riveted, if desired. The side members of the frame member 17 snugly fit within the side members 11 of the 50 rectangular frame 8, and the corner portions of the end members 20 are provided with vertically extending threaded openings 21 for receiving elevating screws 22 journaled in the corner portions of the rectangular frame 8. Said elevating screws have 55 beveled gears 23 mounted on their lower end portions which mesh with other bevel gears 24 also journaled in the rectangular frame. The gears 24 are mounted on transverse shafts 25 and said shafts have sprocket 60 wheels 26 mounted thereon, and sprocket chains 27 carried by said sprocket wheels extend to other sprocket wheels 28 mounted on a central transverse shaft 29. The shaft 29 projects beyond the side portion 65 of the rectangular frame and is

arranged to receive a cranked handle 30 for manually turning the shafts to elevate the form frame 17, as illustrated in part in Fig. 1. In turning the shafts, the form frame can be elevated a sufficient 70 distance to clear the partly set concrete blocks so that moisture laden air or steam can circulate more freely around the blocks during the curing operation.

Concrete blocks are usually of hollow construction, and to maintain the core members 31, necessary in forming the hollow construction, in position, the bottom portion 13 of the rectangular frame is provided with upstanding pins 32 which enter holes 33 75 in the core members 31. Said core members are formed with central under cut openings 34 for receiving T-shaped locking members 35, so that when the T-shaped members 35 are turned a one-quarter turn, the lower or cross portion 35' of said members will extend beneath the shoulders 34' of the under cut openings 34 and lock the core members to said T-shaped members. A core frame 36 mounted on top of the mold frame member 17 is formed in part of transverse frame members 36' through which the stem portions of the T-shaped members extend and are journaled. Slotted arms 37 secured to the upper ends of the stem portions are 80 adapted to be moved a quarter turn by reciprocal bars 38 having upstanding pins 39 which extend through the slots of said arms. As thus constructed, all of the cores may 85 be locked to the core frame and the upward movement of the mold frame will also elevate the core members to clear the partly set concrete blocks. Said core members 31 are tapered downwardly, as clearly shown 90 in Fig. 2, to permit easy withdrawal of the core members from the core openings of the blocks. The frame members or sections 15 and 16 are provided with molds, cores and frames similar to the section 8, and said parts are used in said upper sections in exactly 95 the same manner as similar parts are used in the lower section 8.

In use the two upper sections together with the core frame of the lower section are removed and the concrete in liquid form is poured into the forms until they 100 are filled. The core frame of the lower section is then placed in position on said lower frame and the second section is then placed in position above the first section but minus its core frame. The molds of the second section are then filled with the concrete and when filled the core frame is placed thereon 105 and the third section minus its core frame is then placed on the second frame and the molds are likewise filled with concrete and the core frame is then placed in position on said upper frame. The machine may now 110 be rolled into a steam curing room to expedite the curing of the blocks. Now, as 115

120

125

130

soon as the concrete has set sufficiently to hold its shape, the arms of the core frames are turned to lock the core members thereto and the shafts are turned to cause the screws 5 to raise and separate the molds and the core members from the partly set blocks, and due to the fact that the blocks are all spaced apart, the operation is further expedited. The separation of the blocks also permits 10 the application of moisture to all sides of the blocks. When the blocks are in condition to be removed from the machine the upper cores and molds are first removed, and the blocks can then be easily removed 15 from the rectangular frame or the entire upper frame can be removed with the blocks thereon, and the blocks then can be removed from said frame. The blocks from the remaining sections are removed in the same 20 manner. After removal from the machine, the blocks may be further cured as desired.

From the foregoing description it will be seen that the concrete molding machine is of very simple construction, and a large 25 number of blocks may be molded at one time.

What we claim as our invention is:

1. A molding machine, comprising a frame, a plurality of mold and core members 30 removably mounted thereon, a second frame removably mounted on the first frame, a plurality of mold and core members removably mounted on the second frame, and means on the frames for elevating 35 the mold and core members.

2. A molding machine, comprising a frame, a plurality of mold and core members removably mounted thereon, a second frame removably mounted in spaced relation 40 on the upper portion of the first frame, a plurality of mold and core members removably mounted on said second frame, and means on each frame for independently elevating the mold and core members.

45 3. A molding machine, comprising a frame a plurality of mold and core members removably mounted thereon, a second frame having legs which engage the first frame to hold the second frame in spaced relation above the first frame, a plurality 50 of mold and core members removably mounted on the second frame, and screw means on each frame for independently elevating and holding the mold and core members in elevated position.

60 4. A molding machine, comprising a rectangular frame, a plurality of mold and core members removably mounted therein, a second rectangular frame having corner legs which engage the first frame to hold the second frame in spaced relation above the first frame, a plurality of mold and core members removably mounted in the second frame, said mold member 65 having threaded corner portions, and screws

carried by the frame members and engaging the threaded portions for elevating the mold and core members.

5. A molding machine, comprising a rectangular frame having a bottom portion, 70 a plurality of mold members removably positioned therein, core members removably resting on the bottom portion, a core frame resting on the mold members and removably engaging the core members, a second rectangular frame having a bottom portion and legs which engage the first frame to hold the second frame in spaced relation above the first frame, a plurality of mold members removably positioned in the second frame, core members removably resting 75 on the bottom portion of the second frame, a core frame resting on the mold members of the second frame and removably engaging the core members, said mold members having threaded portions, and screws carried by the respective frame members and engaging the threaded portions of the mold members for elevating the mold members. 80

6. A molding machine, comprising a rectangular frame having a bottom portion, a plurality of mold members removably positioned therein, core pins connected to the bottom portion, core members removably engaging the core pins, core frames resting on the mold members and removably engaging the core members, a second rectangular frame having a bottom portion and shoul- 90 dered legs which removably engage the first frame to hold the second frame in spaced relation above the first frame, core pins connected to the second frame bottom portion, core members removably engaging the core pins, a plurality of mold members removably positioned in the second frame, core frames resting on the mold members of the second frame and removably engaging the core members, said mold members having 95 threaded portions, screws carried by the respective frame members and engaging the threaded portions of the mold members for independently elevating the mold and the core members of each frame, and means for rotating all of the screws of each rectangular 100 frame simultaneously. 110

7. A molding machine, comprising a rectangular frame having a bottom portion, a plurality of mold members removably positioned therein, core pins connected to the bottom portion, core members removably engaging the core pins, core frames resting on the mold members and removably engaging the core members, a second rectangular frame having a bottom portion and shoul- 120 dered legs which removably engage the first frame to hold the second frame in spaced relation above the first frame, core pins connected to the second frame bottom portion, core members removably engaging the core 125

pins, a plurality of mold members removably positioned in the second frame, core frames resting on the mold members of the second frame and removably engaging the core members, said mold members having threaded portions, screws carried by the respective frame members and engaging the threaded portions of the mold members for independently elevating the mold and the core members of each frame, and gear and sprocket chain means for rotating all of the screws of each rectangular frame simultaneously.

8. A molding machine, comprising superimposed rectangular frames removably connected together in spaced relation, each frame having a bottom portion provided with core holding means, core members removably engaging the core means, mold members removably positioned within the respective frames and having threaded portions, screws engaging the threaded portions, core frames carried by the mold members and removably engaging the core members, and means for rotating all of the screws of each rectangular frame simultaneously.

9. A molding machine, comprising superimposed rectangular frames removably connected together in spaced relation, each frame having a bottom portion provided with core holding means, core members removably engaging the core means, mold members removably positioned within the respective frames and having threaded portions, screws engaging the threaded portions, core frames carried by the mold mem-

bers and removably engaging the core members, horizontal shafts carried by the rectangular frames and having beveled gear connections with the screws, and means for rotating all of the screws of each rectangular frame simultaneously.

10. A molding frame, comprising a rectangular frame mounted on wheels and having a bottom portion, superimposed rectangular frames removably mounted on the first frame in spaced relation and having bottom portions, mold and core members removably positioned in each rectangular frame, said mold members having threaded portions, core frames carried by the mold members and movable to lock all of the core members of each rectangular frame to move with the mold members, screws engaging the threaded portions of the mold members for elevating the mold and core members above the rectangular frames, and means for rotating all of the screws of each rectangular frame simultaneously.

11. In a sectional gang molding machine having a number of sections and partitions and cores in each section, means for simultaneously raising or removing all partitions and cores contained in one section, in one operation.

12. In a molding machine having a number of partitions and cores, means for simultaneously raising or removing all partitions and cores in one operation.

In testimony whereof, we affix our signatures.

ARTHUR WHITE.
JACOB J. MOHR.
